UNITED STATES PATENT OFFICE.

CHARLES SEYMOUR, OF DEFIANCE, OHIO, ASSIGNOR TO THE DEFIANCE MACHINE WORKS, OF DEFIANCE, OHIO, A CORPORATION OF OHIO.

CUTTER-HEAD.

SPECIFICATION forming part of Letters Patent No. 686,548, dated November 12, 1901.

Original application filed May 7, 1901, Serial No. 59,133. Divided and this application filed July 16, 1901. Serial No. 68,485.
(No model.)

To all whom it may concern:

Be it known that I, CHARLES SEYMOUR, a citizen of the United States, and a resident of Defiance, in the county of Defiance and State 5 of Ohio, have invented a new and Improved Cutter-Head, of which the following is a full, clear, and exact description, this being a division of the application for Letters Patent of the United States for a spoke-tenoning 10 machine, Serial No. 59,133, filed by me on May 7, 1901.

The invention relates to woodworking machinery; and its object is to provide a new and improved cutter-head more especially designed 15 for use on spoke-tenoning and similar machines and arranged to permit the operator to conveniently, quickly, and accurately adjust the several cutters and to securely hold the same in place to insure uniform work.

20 The invention consists of novel features and parts and combinations of the same, as will be fully described hereinafter and then pointed out in the claims.

A practical embodiment of the invention 25 is represented in the accompanying drawings, forming a part of this specification, in which similar characters of reference indicate corresponding parts in all the views.

Figure 1 is a front face view of the improvement. Fig. 2 is a sectional side elevation of the same on the line 2 2 in Fig. 1. Fig. 3 is a rear face view of the same. Fig. 4 is a front elevation of one of the carriers for the miter-cutter. Fig. 5 is an enlarged inner face view 35 of the cam for adjusting the cutter-head. Fig. 6 is a plan view of the key-pinion for turning the cam and adjusting the miter-cutters. Fig. 7 is a side elevation of the spoke before forming the tenon, the point, and the miter; 40 and Fig. 8 is a like view of the finished spoke.

The improved cutter-head illustrated in the drawings has a body G, which is essentially of disk form and integrally projects from a hub G', adapted to be secured in the usual 45 manner to a revolving spindle. On the body G are mounted a set of tenon-cutters R, a set of miter-cutters R', a set of pointing-cutters R², and a set of shoulder-cleaning cutters R³, all arranged in such a manner that when the 50 end B² of a spoke B passes between a pair of

such revolving cutter-heads then said spoke end is dressed and the tenon B', the point B³, the miters B⁴, and the shoulders B⁵ are all accurately formed at one operation.

Each set of cutters consists, preferably, of 55 two cutters, and the cutters R R² R³ are mounted in the usual manner on the body G, while the miter-cutters R' are each adjustably secured on the inclined top S' of a carrier S by means of bolts R⁴, each carrier S 60 being mounted to slide in guideways G³, formed radially on the face of the cutter-head body G². A bolt S², screwing in the carrier S and extending through an elongated slot G⁴ in the body G, serves to secure the carrier 65 firmly in place after the carrier is adjusted in its guideways G³.

On the face of each carrier S, at or near the inner end thereof, are formed segmental teeth S³ (see Figs. 2 and 4) in mesh with a spiral 70 rib S⁴, formed on the inner face of a ring-shaped cam S⁵, mounted to turn on the hub of the body G, the cam being held in position on the hub by a retaining-ring G⁵, as indicated in Figs. 1 and 2. The peripheral face 75 of the cam S⁵ is provided with a gear-wheel S⁶, adapted to be engaged by a pinion S⁷ in the form of a key having a handle S⁸, (see Fig. 6,) adapted to be set in the body G. When the key-pinion S⁷ is placed in position in one 80 of the bearings G⁶, it is in mesh with the gear-wheel S⁶, and when the operator now turns the handle S⁸ then the pinion S⁷ imparts a rotary motion to the gear-wheel S⁶ and the cam S⁵ and causes the spiral rib S⁴ thereof to 85 move the carriers S simultaneously inward or outward, according to the direction in which the key-pinion S⁷ is turned. Thus by the arrangement described the operator can move the carriers S, and consequently the 90 miter-cutters R', outward or inward to cut the miters B⁴ the desired thickness. When the adjustment has been made, the operator simply removes the key-pinion S⁷ from the bearing G⁶, it being understood that when the 95 adjustment has been finished and the bolts S² screwed up then the several parts are securely locked in position on the cutter-head body G².

Having thus fully described my invention, 100

I claim as new and desire to secure by Letters Patent—

1. A cutter-head, comprising a body having radial guideways, cutter-carriers mounted to slide therein, a cam mounted to turn on said body and having on its face a spiral cam engaging teeth on said carriers, a gear-wheel on said cam, and a key-pinion removably held in a bearing in said body, to engage said gear-wheel, as set forth.
2. A cutter-head, comprising a central body provided with radially-disposed guideways and with slots, radially-movable cutter-car-

riers slidably mounted in said guideways, a cam revolvably connected with said central body and engaging said cutter-carriers for sliding the same, and bolts passing through said slots for securing said central body and said cutter-carriers rigidly together.

In testimony whereof I have signed my name to this specification in the presence of two subscribing witnesses.

CHARLES SEYMOUR.
